UNITED STATES PATENT OFFICE.

GODFREY ENGEL, OF SOUTH BALTIMORE, MARYLAND.

CLOSURE FOR MANHOLES.

SPECIFICATION forming part of Letters Patent No. 540,965, dated June 11, 1895.

Application filed September 4, 1894. Serial No. 522,068. (No model.)

To all whom it may concern:

Be it known that I, GODFREY ENGEL, a citizen of the United States, residing at South Baltimore, in the county of Anne Arundel and State of Maryland, have invented certain new and useful Improvements in Closures for Manholes; and I do hereby declare the following to be a full, clear and exact description of the invention, such as will enable others skilled in the art to which it appertains to make and use the same.

My invention relates to devices for closing man or hand holes in the sides of boilers or other vessels; and my invention consists in the novel means employed for centralizing the cover of the man or hand hole over the opening, in order to secure uniform lap of the cover upon its seat, in the novel means employed for locking the bolt by which such cover is held in place, and preventing the bolt from turning, and in the novel construction and arrangement of the parts constituting my improved closure.

The objects of my invention are, first, to provide a closure for man or hand holes or similar apertures in vessels, so constructed that pressure within the vessel will tend to keep the joint between the cover and its seat tight; second, to provide a closure in which there shall be only one joint, and to so form the parts at this joint that leakage shall be improbable; third, to provide a closure which shall have as few parts as possible; fourth, to provide a closure in which such machining of the parts as may be necessary may be readily done; fifth, to provide means for centralizing the cover over the opening to secure equal lap at the joint; sixth, to provide means for preventing turning of the bolt which holds the cover in place, when its nut is screwed on or off, and, seventh, to provide a closure which shall be strong, durable, efficient in action, and as inexpensive as possible. These objects are attained in the closure herein described and illustrated in the drawings which accompany and form a part of this application, in which the same reference numerals indicate the same or corresponding parts, and in which—

Figure 1 is a plan view of the closure, showing the man or hand hole, with the cover in place therein, the cover bolt being sectioned and the yoke removed in order to show certain recesses in the cover and in the flange

surrounding the opening. Fig. 2 is a sectional elevation taken on the line xx of Fig. 1, which line is the minor axis of the elliptical man or hand hole, the yoke being shown in elevation. Fig. 3 is a section taken on the line yy of Fig. 1, which line is the major axis of the ellipse; and Fig. 4 is a detail plan view of the yoke inverted.

In the drawings, 1 is the aperture forming the man or hand hole, over which projects a flange, 2, the opening 3 in which is longer in one direction than the other, and in the drawings is shown as an ellipse. The flange 2 may be a portion of the side of the vessel, if that vessel be of cast metal; but where, as in the case of most steam boilers, the vessel is composed of sheets of wrought material, the flange 2 may be secured to the side of the vessel by bolts or rivets.

Within the aperture 1, and bearing up against the inner side of the flange 2, is the cover-plate 4, which cover-plate is larger than, but similar in shape to the opening 3, in the flange 2, the shorter axis of the cover being shorter than the longer axis of the opening 3. This cover-plate 4 is provided with a central boss 5, which may be circular, and is of a height sufficient to hold in place a packing ring 6, if it be desired to use packing. The cover-plate is likewise provided with a further central boss 7, which is provided with a groove 8 coinciding with one of the axes of the cover-plate, and of a width sufficient to receive projecting lugs of the yoke, to be hereinafter described.

Within the cover-plate 4 is a central circular chamber 9, to the bottom of which the groove 8 extends. This chamber is of a diameter considerably greater than the width of the groove 8.

10 is the yoke, which extends across the opening 3 in the ordinary manner, its ends resting on the flange 2. The flange 2 is provided with grooves 11, 11, coinciding with one of the axes of the opening 3, into which fit the ends of the yoke 10, thus centralizing the yoke as to one axis of the opening 3. The yoke is likewise provided with shoulders 17, 17, fitting closely against the edges of the opening 3 in the flange 2, which centralize the yoke as to the other axis of the opening 3. At its center the yoke is provided with a bolt hole 12 through which passes the cover bolt 13. The head of this bolt is flattened on two

opposite sides, so that it may pass through the groove 8 into the chamber 9 in the cover-plate, and the length of the head 14 is such that when in the chamber 9 it may be turned 5 at right angles to the groove 8, so as to engage with the cover-plate.

The yoke 10 is provided with inwardly projecting lugs 15, 15, on either side of the bolt hole 12, which are of a width such that they 10 may enter the groove 8 in the cover-plate, and of a length such that they project nearly to the bottom of the groove 8. When in place, they are closely adjacent to the flattened sides of the head 14 of the bolt, and therefore lock 15 this bolt in place, preventing it from turning when the nut 16 is screwed on or off. These lugs 15 fit closely within the groove 8 both at the ends and sides, and therefore centralize the cover-plate as to the yoke, and therefore 20 as to the opening 3.

The method of using my improved closure is as follows:—If a packing ring 6 is to be used, the packing ring is first put in place over the boss 5. The cover-plate is then 25 passed through the opening 3, which may be effected by holding it by means of its central boss, turning it somewhat from the position which it occupies when in place, and tilting it so as to pass one end through the opening 30 first. The cover-plate is then turned into its proper position, and held up against its seat while the bolt 13 is put in place, by inserting its head into the groove 8 and pushing it down to the bottom of the groove, and then 35 turning the head in the chamber 9 until it is at right angles to the groove 8. The yoke 10 is then passed over the bolt, its ends entering the grooves 11, 11, in the flange 2, its shoulders 17, 17, engaging the sides of the 40 opening 3, and its lugs 15, 15, entering the groove 8, centralizing the cover, and, since these lugs fit closely against the head of the bolt, locking it in place and preventing it from turning. The nut 16 is then put upon 45 the bolt and screwed down until the cover-plate 4 and packing 6 are pressed firmly against the flange 2, forming a tight joint.

It will be seen that the only machining of surfaces required in this closure is on the 50 cover and on the seat therefor on the flange 2, and since the boss of the cover is circular, and does not come close to the edge of the flange 2, the surface of the cover may be machined without difficulty. With smooth castings, where packing is used, no machining 55 will ordinarily be required. If a ground joint between the cover and flange is desired, this joint may be ground without difficulty after the cover is in place. It will likewise be observed 60 that pressure within the vessel has the effect of pressing the cover 4 more firmly against the flange 2, thus decreasing liability to leakage.

Having thus completely described my invention, what I claim, and desire to secure by Letters Patent, is—

1. In a closure for man- and hand-holes, the

combination, with a vessel having an aperture therein and a cover for such aperture, of a yoke bridging such aperture, recesses in the 70 rim of such aperture adapted to receive said yoke and to centralize the same in one direction, inwardly projecting shoulders on said yoke engaging with the edge of said rim and adapted to centralize said yoke in the other 75 direction, and a bolt passing through said yoke and adapted to hold said cover in place, substantially as described.

2. In a closure for man- and hand-holes, the combination, with a vessel having an aperture therein, and a cover for said aperture, of a yoke bridging such aperture, means for centralizing said yoke with respect to said aperture, a bolt passing through said yoke and adapted to hold said cover in place, a groove 80 within said cover, and a projection on said yoke adapted to enter said groove and to centralize said cover with respect to said yoke, substantially as described.

3. In a closure for man- and hand-holes, the combination, with a vessel having an aperture therein, and a cover for such aperture, of a yoke bridging such aperture, a bolt having a non-cylindrical portion engaging said cover, passing through said yoke, and adapted 95 to hold said cover in place, and projections from said yoke engaging said non-cylindrical portion of said bolt and adapted to prevent it from turning, substantially as described.

4. In a closure for man- and hand-holes, the combination, with a vessel having an aperture therein, a cover for such aperture, a yoke bridging such aperture, and a chamber within said cover, of a bolt passing through said yoke and having a head adapted to enter 100 said chamber and engage with said cover, a groove in said cover adjacent to the head of said bolt when the latter is in place within said cover, and projections on said yoke adapted to enter said groove and engage with 105 the head of said bolt, substantially as described.

5. In a closure for man- and hand-holes, the combination, with a vessel having an aperture therein, a cover for said aperture, a 110 yoke bridging said aperture, a chamber within said cover, and a groove in said cover communicating with said chamber, of a bolt passing through said yoke and having a head flattened in one direction and elongated in 115 the other direction, and adapted to enter the groove and chamber in said cover, and projections on said yoke adapted to enter said groove when the head of said bolt is in place within said chamber, and to engage the ends 120 and sides of said groove and the head of said bolt, substantially as described.

In testimony whereof I affix my signature in presence of two witnesses.

GODFREY ENGEL.
